(57) **CLAIM**

The ornamental design for a lock for fishing lure clip, substantially as shown.

DESCRIPTION

FIG. 1 is a perspective view of a lock for a fishing lure clip showing my new design, with the fishing lure clip to which the lock is attached being shown in phantom;

FIG. 2 is a bottom plan view thereof;

FIG. 3 is a left side elevational view thereof;

FIG. 4 is a top plan view thereof;

FIG. 5 is a right side elevational view thereof;

FIG. 6 is a front elevational view thereof;

FIG. 7 is a rear elevational view thereof; and,

FIG. 8 is a perspective view of a second embodiment of a lock for a fishing lure clip showing my new design.

The broken line showing of a fishing lure clip in FIG. 1 is for illustrative purposes only and forms no part of the claimed design.
